UNITED STATES PATENT OFFICE

GEORGE LEWIS, OF ELIZABETH, NEW JERSEY, ASSIGNOR TO ARCTURUS RADIO TUBE COMPANY, OF NEWARK, NEW JERSEY, A CORPORATION OF DELAWARE

DESIGN FOR A PHOTOLYTIC CELL

Application filed March 20, 1930. Serial No. 34,977. Term of patent 14 years.

To all whom it may concern:

Be it known that I, GEORGE LEWIS, a citizen of the United States, residing at Elizabeth, in the county of Union and State of New Jersey, have invented a new, original, and ornamental Design for Photolytic Cell, of which the following is a specification, reference being had to the accompanying drawing, forming a part of the same, in which—

Fig. 1 is a front view of the photolytic cell showing my new design; and

Fig. 2 is a side view of the cell shown in Fig. 1.

In the drawings Fig. 2 is shaded for orange and black.

I claim:

The ornamental design for a photolytic cell as shown and described.

GEORGE LEWIS.
